CHARTING DEVICE

Ralph W. Walsh, Los Angeles, Calif.

Application November 14, 1932
Serial No. 642,487

5 Claims. (Cl. 164—86)

This invention relates to a charting or recording device, particularly adapted to be used in checking the parts of a motor vehicle or other mechanism requiring lubrication.

5 It is well understood that in order that a motor vehicle may operate in the most efficient manner it is necessary that certain parts be lubricated at predetermined time intervals. As the driver of a motor vehicle usually leaves it at a service station for this purpose (while attending to other business) he has no knowledge of how well the job has been done, for the reason that the attendant often overlooks or fails to lubricate all the necessary parts, either due to unfamiliarity with 10 the arrangement of such parts or because of neglect. Although the attendant may fully understand the arrangement of parts to be lubricated, he often starts lubricating parts which will cause his hands to become greasy and oily, then lubricates the parts which require clean handling, such as door hinges, knobs, etc. Such procedure usually results in the body or the interior of the car becoming soiled with grease or oil.

It is therefore an object of the present invention to provide a charting device which will enable the attendant of a service station to quickly locate in sequence the parts of a motor vehicle which require lubrication so that none will be overlooked.

20 Another object is to provide a charting device of the character described, including a charting strip and means for perforating the same, so that the owner or driver of the machine, by referring to the perforated strip may determine whether 25 or not his car has been completely lubricated.

Other objects and advantages will be apparent from the following description, reference being had to the accompanying drawing, in which:

Fig. 1 is a perspective view of the charting 40 device.

Fig. 2 is a front elevation showing the straps applied thereto supporting the same on a person's body.

Fig. 3 is an enlarged vertical section taken 45 through the punch.

Fig. 4 is a section taken on line 4—4 of Fig. 3.

Fig. 5 is a section taken on line 5—5 of Fig. 3.

Fig. 6 is a top plan view with the cover or top plate opened.

50 Fig. 7 is a fragmentary face view of the charting strip illustrating an example of the characters thereon.

Referring more specifically to the drawing, 10 generally designates a magazine or casing which 55 is preferably formed from sheet metal stampings.

Casing 10 consists of an upper portion or chamber 12 in which is mounted the perforating or recording mechanism, and depending from the chamber is pocket 14, that serves to receive charting strip designated at S.

Arranged in upper portion 12 of the casing is a horizontally disposed guide plate 13 that slidably supports the charting strip, the plate having downwardly curved ends 16 and side flanges 18, which flanges engage and are secured to the side 60 walls 19 of the casing by screws or rivets designated at 20.

Charting strip S is folded in zig-zag formation and has printed or otherwise formed thereon indicia or characters designated at I (see Fig. 7), 70 which may illustrate, for example, various parts of a motor vehicle that should be lubricated at predetermined intervals.

One end of charting strip S is adapted to be passed over plate 13 and connected to a roller 21 75 that serves to move the strip across said plate so that the characters thereon may be successively observed, the roller having a longitudinal kerf or groove 22 formed therein through its length to receive the end of the strip, also to permit its 80 removal after said strip has been wound thereon.

Roller 21 is removably mounted in diagonally disposed recesses 23 formed in side walls of the casing and is held in place against shifting by grooves 24 formed adjacent each end thereof that 85 engage the lower ends of the recesses, the roller being provided with a knurled head 25 to facilitate turning of the same.

Slidably mounted in aligned openings 26 and 27 respectively formed in the wall 29 of the upper 90 portion of the casing and a guide block 30 secured to one of the flanges 19 is a push pin 32 which serves to perforate and thereby form a record on the charting strip.

Pin 32 is provided with a reduced diameter 95 portion 33 that is arranged to pass into the opening 34 of a die 35 disposed directly above block 30, and formed on the lower end of the pin is a button 35', and encircling said pin between block 30 and a shoulder 36 formed thereon 100 is an expansion coil spring 37 which serves to hold the pin clear of the strip.

Hingedly connected as indicated at 38 to the casing is a cover 40 (which serves to protect the strip) having an opening 41 formed in its top 105 wall 42, closed by a transparent plate 43, through which the indicia I on the strip may be observed, the plate being held in place by a suitable frame 44.

Pivottally connected to the cover adjacent one 110

end thereof is a suitable latch 45 which is arranged to engage a keeper or lug 46 formed on the end wall 47 of the casing, the latch being secured to and operated by a suitable handle 48.

- 5 Secured to the top of the cover is a spring tensioning device 49 that engages the strip when the cover is closed. Secured to the side wall of the casing and engaging the end face of the roller is another spring tensioning device 51
 10 which coacts with the aforesaid device to hold the strip taut on the plate. The cover is provided with flanges 50 which engage the side walls of the casing, and formed in said flanges are semicircular recesses (not shown) which engage the grooves in the roller and thereby hold it in place within the recesses formed in the casing when said cover is closed.

From the foregoing it will be apparent that by turning roller 21, then pressing on push pin 32, the strip may be perforated at intervals throughout its length.

Referring to Fig. 7, the indicia I printed on strip S includes illustrations of the various parts of a motor vehicle requiring lubrication and 25 accompanying directions designated at D indicating where and how often such parts should be lubricated.

It is to be understood that the illustrations above referred to are arranged in proper sequence so that attendants will start in lubricating the parts which will not cause their hands to become greasy.

The charting device is adapted to be carried by the attendant while lubricating the machine and is provided with a neck strap 52 and waist strap 53 for this purpose, as clearly shown in Fig. 2.

In operation, the attendant first refers to the illustration appearing through the opening in the casing, and lubricates the parts thus indicated. He then presses button 35 which perforates the strip adjacent the illustration. Roller 21 is then turned to bring the succeeding illustration into view and the above operation repeated until all parts of the machine have been lubricated.

After lubricating the parts and recording such operations in the manner above referred to, the strip which is then wound on the roller is adapted 50 to be removed from the casing. This may be easily done by opening cover 40, lifting roller 21 out of the recesses 23, and removing the strip

therefrom. The roller may then be returned to the casing for another operation.

From the foregoing it will be apparent that the charting device not only provides means whereby an accurate record indicating whether a machine has been completely lubricated may be obtained, but materially aids the attendant while performing such operation.

I claim:

1. A charting device comprising a casing having a sight opening formed therein for the reception of a folded charting strip having characters formed thereon, a strip winding roll for connection with one end of the charting strip removably mounted in said casing, and means for making a record on said strip. 85
 90

2. A charting device comprising a casing for the reception of a folded charting strip, a strip winding roll for connection with one end of said strip and removably mounted in said casing, and means for making a record on said strip. 95

3. A charting device comprising a casing for the reception of a removable charting strip having characters formed thereon, a cover having a sight opening formed in its top wall hingedly connected to said casing, means for supporting the charting strip within said casing, a strip winding roll for connection with one end of said strip and removably mounted in said casing, means for making a record on said strip, means 100 engaging the strip for tensioning the same, and other tensioning means secured to said casing engaging said roll for holding said strip taut on said plate. 105

4. A charting device comprising a casing having a sight opening formed therein for the reception of a folded removable charting strip having characters formed thereon, a strip winding roll removably mounted in said casing for actuating said strip, said roll having a longitudinal groove 115 formed therein throughout its length for connecting one end of the strip thereto and to permit of its removal after the same has been wound thereon.

5. A charting device comprising a housing having a sight opening formed therein, said housing adapted to receive a folded charting strip having characters formed thereon, a strip winding roll mounted in said housing, one end of the charting strip being connected thereto, and means to form 120 a record on the strip at intervals. 125
